UNITED STATES PATENT OFFICE.

WILEY M. GRISHAM, OF OXVILLE PRECINCT, SCOTT COUNTY, ILLINOIS.

CAR-COUPING.

SPECIFICATION forming part of Letters Patent No. 248,452, dated October 18, 1881.

Application filed June 11, 1881. (Model.)

To all whom it may concern:

Be it known that I, WILEY M. GRISHAM, a citizen of the United States, residing in Oxxville precinct, in the county of Scott and State of Illinois, have invented a new and useful 5 Car-Coupler, of which the following is a specification.

My invention relates to that class of couplers in which the operation of coupling is automatically performed and that of uncoupling effected from either of the sides of the cars.

The object of my invention is to construct a coupler which shall be safe to uncouple, simple in construction, and effective in operation.

My invention consists in various novel devices for accomplishing these purposes, all of which will be hereinafter fully explained.

In the drawings, Figures 1 and 2 represent perspective views of my improved coupler in position for engagement; Fig. 3, a detail view of the coupling-pin and attachments; Fig. 4, a detail view of the coupling-hook, and Fig. 5 a detail view of the weighted coupling-hook guide.

Similar letters of reference indicate corresponding parts throughout the different views.

N is the bumper, in a slot of which the coupling-hook H is pivoted by a short bolt, I, passing through an eye formed in the rear end of said hook. In the opposite side of the bumper a second slot, L, is formed, extending the whole depth of the same, and having flaring edges. In the lower forward part of said flaring edges an angle-plate, A, provided with a weight, C, upon its lower end, is pivoted by a short bolt passing through part of the bumper, and an eye, B, formed in the angle of said plate. The longer arm of the plate, in its normal position, rests upon shoulders formed on the sides of the slot, and extending from the lower part of the same upward and backward to the coupling-pin. By this construction the plate A acts as a guide for the hook H while the cars are being coupled, and, after being borne backward by the hook in the operation of uncoupling, is returned to its normal position by the weight C.

In the rear of the upper edge of guide A a transverse hole is formed in the bumper,

through which the coupling-pin D passes. The 50 outer extremity of said pin is provided with a curve or arm, E, upon whose end is formed a ring, through which passes a rod, F, provided with collars on either side of said ring, and having weighted ends F'. There are also 55 formed upon rod F, in the same plane with the weighted ends F', stops G, which work in recesses m, formed in the sides and top of the bumper. By this construction, when the weighted ends F' are turned through an arc of one 60 hundred and eighty degrees, the rods may be laterally moved a part of their length and the pin D withdrawn from its position across the aforesaid slot, whereby the hook H is uncoupled. Upon dropping the weighted end the rod is 65 turned, and one of the stops G prevents the return or jarring of said coupling-pin to its normal position. When the pin is in place the other stop G engages with the sides of the aforesaid recess and prevents uncoupling. 70

In the middle of the face of the bumper is the recess J, provided with flaring sides, and through the forward part of the upper and lower sides a perforation, K, is made, whereby, when it is desired, the ordinary coupling link 75 and pin may be used.

The operation of my improved coupler is as follows: When two cars fitted with the same approach each other the hooks H first come in contact with the guide-plates A at about half-way of the latter's length. Following the incline of said plates they finally drop over the pins D, and the cars are coupled. When it is desired to uncouple said cars the weighted ends F' are made to describe an arc of one 80 hundred and eighty degrees, one of the rods F is pushed and the other pulled, and the pins D are thereby withdrawn and the cars uncoupled. In the separation of the latter the guides A are drawn outwardly until the hooks 85 pass over the ends, when the weighted arms F' cause their return to normal position.

Having thus described my invention, what I claim is—

1. The combination, with the bumper N, of 90 the coupling-pin D, arm E, and rod F, substantially as and for the purposes set forth.
2. The combination, with the bumper N, pro-

vided with recesses M, and the pin D, of the rod F, weighted ends F', and stops G, substantially as and for the purposes described.

3. The combination, with the bumper N and 5 pin D, of the pivoted angle-plates A C, substantially as and for the purposes described.

4. The within-described car-coupling, consisting of bumper N, hook H, pivoted weighted

angle-plate A C, pin D, arm E, and rod F, provided with weighted arms F' and stops G, substantially as and for the purposes described. 10

WILEY MASON GRISHAM.
